UNITED STATES PATENT OFFICE.

LOUIS A. BARR, OF PITTSBURGH, PENNSYLVANIA; MARGARET L. BARR ADMINISTRATRIX OF SAID LOUIS A. BARR, DECEASED.

COLLAPSIBLE MANDREL.

1,202,775.

Specification of Letters Patent. Patented Oct. 31, 1916.

Application filed June 28, 1915. Serial No. 36,731.

To all whom it may concern:

Be it known that I, LOUIS A. BARR, a resident of Pittsburgh, in the county of Allegheny and State of Pennsylvania, have invented a new and useful Improvement in 5 Collapsible Mandrels, of which the following is a specification.

This invention relates to a collapsible mandrel and particularly to a mandrel designed for use in the formation of tubes by the lap weld process.

It has heretofore proved impracticable to form tubes of any length around a mandrel, owing to the difficulty of removing a solid 15 mandrel from the completed tube.

One object of the invention is to provide a mandrel which may be collapsed in order to permit its withdrawal from a completed tube, and which when assembled is of sufficient 20 strength and rigidity to fulfil all of the requirements of a mandrel used in the formation of iron or steel tubes, that is sufficiently strong and rigid to have skelp wrapped around it and to be subjected to 25 the action of the rolls in the formation of tubes by the lap weld process.

A further object of the invention is to provide a collapsible mandrel which comprises but few parts and which may have 30 walls of such thickness that they will effectually withstand the heat incurred during the process of forming tubes, and the operating parts of which are of sufficient strength to withstand strain and rough 35 usage.

A still further object is to provide a mandrel which may not only be readily collapsed, but which may also be re-assembled by a similar action and without the use of 40 any tools.

The invention comprises the construction and arrangement of parts as hereinafter described and claimed.

In the accompanying drawings, Figure 1 45 is a longitudinal section through the mandrel taken on the vertical diameter thereof; Fig. 2 is a similar view but illustrating the position of the operating parts when the mandrel is collapsed; Fig. 3 is an end view 50 of the mandrel; Fig. 4 is a similar view showing the mandrel in collapsed condition; Fig. 5 is an end view of a portion of the shell of the mandrel showing a modified form of connection between the smaller seg- 55 ment and the two larger segments of the

mandrel shell; Figs. 6 and 7 are views respectively of the central bar and operating sleeve of the mandrel illustrating the relative positions of the guiding members of the mandrel bar; Figs. 8, 9, 10, 11 and 12 60 illustrate a modified form of the invention; Fig. 8 is a longitudinal sectional view through the modified mandrel on the vertical diameter thereof; Fig. 9 is an end view of the modified mandrel expanded; Fig. 10 65 is an end view of the same collapsed; and Figs. 11 and 12 are detail views of the means for attaching the mandrel bar and operating sheave to the inner surface of the mandrel shell.

The preferred form of the device comprises a pair of relatively large segments 1 and 2 which are connected at one edge by a plurality of hinges 3 and a third segment 4 arranged in assembled condition of the mandrel to enter between the free edges of segments 1 and 2 to form a complete cylindrical body. In collapsing the mandrel segment 4 is drawn inwardly toward the central longitudinal axis of the mandrel by suitable 70 actuating means and the free edges 5 and 6 of the segments 1 and 2 are drawn toward each other until they come in contact at a point on the central vertical axis of the mandrel which is slightly lower than the 75 point reached by the outermost portion of the arc previously formed by the segment 4. It is thus seen that the transverse diameter of the mandrel is materially decreased and the vertical diameter of the same is also de- 80 creased though to a lesser extent.

Upon the pintles 7 of the hinges 3 is mounted a spoke 8 which supports a centrally located solid bar 9 with which it is integrally cast or to which it is rigidly secured. This bar throughout a portion of its length is provided with a slot 10 extending entirely therethrough in a vertical plane, and arranged to receive a guide 11 secured to the inner surface of segment 4 of the 95 mandrel wall. Surrounding the bar 9 is a sleeve 12, slotted at 13 to permit the extension of the guiding member 11 therethrough, and slotted throughout its entire length at another point to permit the passage of spoke 100 8 and guide 11. The guide 11 consists of a plate shown as substantially rectangular in shape, and is provided with one or more slots 14 inclined at an angle from the plane of the diameter of the mandrel. Preferably, 105 110

two of such slots 14 are provided in the guide 11, and through each of these slots passes a pin 15 which is bolted or otherwise rigidly secured at each end to the sleeve 12. At the extremity of each of the slots 14 nearest the central axis of the mandrel the slot is extended rearwardly to form a locking notch 16 for receiving the pin 15 in assembled condition of the mandrel. In order to collapse the mandrel, the sleeve 12 which is preferably provided with a suitable handle or with a hole for receiving a hook, is slid forwardly upon the bar 9, which action causes the guiding pins 15 to move the guide 11 downwardly in the body of the mandrel by means of their engagement in the inclined slots 14.

Each of the segments 1 and 2 of the mandrel wall is connected to the sleeve 12 by a suitable hinged arm. These arms as illustrated in Figs. 1 to 4 inclusive consist of links 17 having at each end an elongated eye 18 interlocking with eye-bolts 19 on the inner surface of the mandrel wall and upon the surface of the sleeve 12. When the sleeve 12 is actuated to collapse the mandrel by removing segment 4 from its circumference, the same action will draw segments 1 and 2 inwardly until their edges 5 and 6 contact, the connection between the elongated eyes 18 and eye-bolts 19 providing a slight amount of lost motion so that the segment 4 is permitted to start upon its downward travel before the segments 1 and 2 are drawn inwardly. The inward movement of the segments 1 and 2 decreases the horizontal diameter of the mandrel considerably, while the upper extremities of their edges 5 and 6 are lowered sufficiently along the vertical axis of the mandrel to break the contact at that point between the mandrel and the inner surface of the completed tube. In order to re-assemble the mandrel the sleeve 12 is moved rearwardly upon the central bar 9, in which action the guide pins 15 act in the slots 14 to raise the segment 4 and to cause it to enter between the edges 5 and 6 of the segments 1 and 2 to reform the cylindrical body of the mandrel. In this action the arms 17 act to force the segments 1 and 2 outwardly and thereby assist the re-assembling operation by opening a space into which the segment 4 may be introduced.

The hinges 3 may be of any desired form but are preferably strap hinges, as shown, arranged with their leaves 20 secured to the inner surface of the segments 1 and 2 and with their pintles 5 lying entirely inwardly of the inner surface of the mandrel, so that the edges 21 and 22 of the segments 1 and 2 will not rotate outwardly an appreciable distance when the segments 1 and 2 are drawn together, and therefore will not counterbalance the decrease in vertical diameter of the mandrel caused by the removal

of the segment 4. The contacting surfaces 5 and 6 of the segments 1 and 2 and 23 and 24 of the segment 4 may be cut on a straight line, as illustrated in Fig. 5, or may be cut to present to each other two surfaces in different planes as illustrated in the remaining figures of the drawings. When the surfaces are plane, as illustrated in Fig. 5, the tubular portion of the mandrel may be formed by cutting a continuous tube into the desired segments, or by any other suitable process of manufacture. When, however, the other form of contacting surface is used the segments comprising the tubular body of the mandrel are formed separately by a casting operation and their contacting surfaces machined in order to secure a good engagement and form a perfectly cylindrical body. The form of contacting surfaces shown in Figs. 1 to 4 of the drawings is the preferred form since it provides an improved locking engagement between the segments which allows the segment 4 to be more readily inserted between the segments 1 and 2 in assembling the mandrel and somewhat increases the rigidity of the mandrel when assembled, since most of the strain incurred in use of the mandrel will be circumferential. This engagement, moreover, allows the segments 1 and 2 to move inwardly toward the vertical diameter of the mandrel a slightly greater distance, and therefore permits either a greater decrease in the vertical and horizontal diameters of the mandrel when collapsed or permits a thickening of the mandrel wall while securing the same collapsed diameters of the mandrel as with the straight engagement between the side segments and the movable segment 4.

Mandrels as thus formed may be made of as great a length as is found practicable without causing sagging of the mandrel when subjected to the heating effect of the skelp in forming the tubes. If the mandrel is to be made of considerable length, the central bar 9 is preferably provided with a spoke 8 at short intervals, and the vertical movable segment 4 is provided with a corresponding member or guide 11 for which additional slots 10 and slots and guiding pins are provided. The hinges 3 between the segments 1 and 2 of the mandrel are preferably spaced at short intervals in order to increase the strength of the construction, and are also preferably formed of as heavy a construction as possible in order to give greater strength to the mandrel. It will be noted that the arrangement of the parts as described permits the mandrel wall to be formed of comparatively great thickness, and that the other parts called upon to resist strains, namely, spokes 8, guides 11, and the guide pins 15 may be of comparatively great thickness and strength. It will be noted that clearance is provided between 130

pin 15 and the under surface of the segment 4, as shown in Fig. 3 of the drawings so that in the construction of the mandrel either the thickness of the shell or the diameter of the pins 15 may be increased to suit the anticipated conditions of use. It is also obvious that the diameter of the bar may be decreased in its relative proportion to the diameter of the shell, as shown, in order to 10 permit a greater degree of clearance within the shell.

In the modification illustrated in Figs. 8 to 12 inclusive of the drawings, an additional movable segment 4^a is provided. This segment is secured to a guide 11^a which enters a suitable slot 10^a in the central bar 9 of the mandrel. Since the spoke 7 is omitted in this modification additional arms are provided between the sleeve and bar and the inner surfaces of the segments 1 and 2 in order to secure a firm and rigid construction. Three arms are hinged on the interior of each of the segments 1 and 2, in any suitable manner, two of the arms 25 being 20 hinged at their outer ends to the sleeve 12 and the other arm 26 extending through a suitable slot 27 in the sleeve and being hinged to the bar 9. Both of the arms 25 and the arm 26 are secured to the interior of the mandrel shell by means of the hinge 28, which has a lost motion connection in the elongated eye 29, the leaf or strap 30 of which is bolted to the inner surface of the shell. The two arms 25 at their opposite 30 ends are secured to the surface of the sleeve by means of hinge 30 bolted to the sleeve through straps 31, while arm 26 is provided at its inner end with a hinge 32 secured to bar 9 by straps 33. In this construction both 40 of the segments 4 and 4^a are withdrawn from the circumference of the mandrel in collapsing the same and the vertical diameter of the mandrel is decreased a correspondingly greater amount than when only one segment 45 is so withdrawn. The guides 11 and 11^a are necessarily located at different points longitudinally of the mandrel as shown in Fig. 8, are provided with slots 14 and 14^a and guiding pins 15 and 15^a corresponding to those 50 illustrated in the other form of mandrel, the slots 14^a being obviously inclined at an angle which is equal to that of the slot 14 but opposite in sense thereto.

The operating parts of the mandrel are 55 susceptible of a number of other modifications without departing from the spirit of the invention as set forth in the appended claims. For example, the arms 17 secured to the inner surface of the segments 1 and 2 60 and to the sleeve 12 may be supplanted by arms of the form illustrated in the modification described above, or similar arms may be utilized to withdraw the segment 4 from the circumference of the mandrel.

65 The mandrel described is readily collapsed

and reassembled, and when assembled forms a strong and rigid construction. The mandrel wall, moreover, is of such thickness that it is not apt to sag when subjected to the heat of the skelp and the pressure of the 70 rolls during the process of forming tubes, and is also enabled to protect the operating parts in the interior of the mandrel from sticking or bending due to the overheating of these parts.

What I claim is:

1. A collapsible mandrel comprising a plurality of segments arranged to form a hollow cylindrical body, a bar supported in the interior of said body, a sleeve slideable upon said bar, a guide secured to the inner surface of one of said segments and arranged to enter slots in said sleeve and bar, said guide being provided with a plurality of angularly disposed slots, and pins secured to 80 said sleeve and passing through the slots in said guide.

2. A collapsible mandrel comprising a plurality of segments arranged to form a hollow cylindrical body, a bar supported in the interior of said body, a sleeve slideable on said bar, a guide secured to the inner surface of one of said segments and passing through slots in said sleeve and bar, and a plurality of pins secured to said sleeve and arranged to extend through angularly disposed slots in said guide and in assembled position of the mandrel parts to enter locking notches in 90 said guide.

3. A collapsible mandrel comprising a 100 plurality of segments arranged to form a hollow cylindrical body, a bar supported in the interior of said body, a sleeve slideable upon said bar, a guide secured to the inner surface of one of said segments and arranged to enter slots in said sleeve and bar, means secured to said sleeve and arranged upon movement thereof to act upon said guide to move said segments inwardly toward the central longitudinal axis of the mandrel, and means secured to said sleeve and arranged upon actuation thereof to collapse the remaining segments of the mandrel wall.

4. A collapsible mandrel comprising a 110 plurality of segments arranged to form a hollow cylindrical body, a bar supported in the interior of said body, a sleeve slideable upon said bar, a guide secured to the inner surface of one of said segments and arranged to enter slots in said sleeve and bar, said guide being provided with a plurality of angularly disposed slots, pins secured to 120 said sleeves and passing through the slots in said guide, and means secured to said sleeve and arranged upon actuation thereof to collapse the remaining segments of the mandrel wall.

5. A collapsible mandrel comprising a 125 plurality of segments arranged to form a hollow cylindrical body, a bar supported in 130

the interior of said body, a sleeve slidable on said bar, a guide secured to the inner surface of one of said segments and passing through slots in said sleeve and bar, a plurality of pins secured to said sleeve and arranged to extend through angularly disposed slots in said guide and in assembled position of the mandrel to enter locking notches in said guide, and means secured to 5 said sleeve and arranged upon actuation thereof to collapse the remaining segments 10 of the mandrel wall.

6. A collapsible mandrel comprising a continuous shell composed of a plurality of 15 segments, a guide secured to one of said segments and provided with an inclined slot, a pin passing through said slot, and movable means arranged to support said pin and when moved to cause it to act upon said 20 guide for lowering the same within said shell.

7. A collapsible mandrel, comprising a continuous shell composed of a plurality of segments, a guide secured to one of said 25 segments and provided with an inclined slot, a pin passing through said slot, movable means arranged to support said pin and when moved to cause it to act upon said guide for lowering the same within 30 said shell, and arms secured to said movable means and the remaining segments of said shell for collapsing said remaining segments.

8. A collapsible mandrel comprising a shell divided into body segments and wedging 35 means, operating means within said shell, and means connecting said wedging means and body segments to said operating means and arranged upon a continuous actuation of the latter to first withdraw said wedging means from the surface of the shell without tending to collapse said body segments and after said withdrawal to act upon 40 said body segments to collapse the same.

45 9. A collapsible mandrel comprising a

hollow cylindrical body divided into body segments and wedging means, a bar supported interiorly of said body, a sleeve slid able on said bar, means on said sleeve connecting the same to said wedging means and arranged upon actuation of said sleeve to withdraw said wedging means positively from the mandrel shell without tending to collapse said body segments, and after said withdrawal to act upon said body segments 50 to collapse the same. 55

10. A collapsible mandrel comprising a shell divided into body segments and a wedge segment, a bar mounted centrally of said shell, a sleeve on said bar and having 60 connection with said wedge segment arranged to withdraw the latter upon actuation of said sleeve, and means for collapsing each of said body segments comprising a pair of interconnected arms pivoted to said 65 bar and sleeve respectively and having a lost motion connection with the interior of said body segments.

11. A collapsible mandrel comprising a shell divided into a wedge segment and body 70 segments, a bar supported centrally of said shell, a sleeve slid able on said bar, a guide secured to the inner surface of said wedge segment and passing through slots in said sleeve and bar, said guide being provided 75 with a plurality of angularly disposed sleeves, pins secured to said sleeve and passing through said slots, and means for collapsing each of said body segments comprising a pair of interconnected arms pivoted to 80 said bar and sleeve respectively and having a lost motion connection with the interior of said body segment.

In testimony whereof, I have hereunto set my hand.

LOUIS A. BARR.
